M. H. RAGGIO

FILING DEVICE

Filed Sept. 23, 1925

FIG. 1.

21 ¹ Inventor
20 Maynard H. Raggio,
by Wallace A. Lane. Atty.

UNITED STATES PATENT OFFICE.

MAYNARD HOLDING BAGGIO, OF CHICAGO, ILLINOIS, ASSIGNOR TO THE CLEMENTSEN COMPANY, OF CHICAGO, ILLINOIS, A CORPORATION OF ILLINOIS.

FILING DEVICE.

Application filed September 23, 1925. Serial No. 58,017.

The present invention relates to filing devices and the like.

Among the objects of the invention is to provide a simple means for effecting a filing space in a drawer or like container without modifying the construction of the drawer, as by taking an existing or ordinary drawer and by a simple change, such as the mere cutting of grooves in opposite sides of vertical walls thereof, and adding thereto, without further change or modification, the members that will effect a filing space and back the articles filed in any number of filings thereof.

The invention also comprehends the idea of making the device adaptable or selective to the use of different sized articles to be filed, such as the filing of cards of different sizes. Selectivity is attained by the invention by providing two or more sets of grooves such that the inserting of the backing means in one set of grooves will provide a filing space for one size of cards and in another set of grooves for another size.

The backing means preferably comprises a movable backing member preferably slideable over or along a rod which may extend into opposed grooves of a set and may be supported therein by any suitable means, such as a partition means or member extending into said groove, the backing member preferably extending laterally from the rod and partition means and into the filing space. The backing member may have a supporting means secured to it as by leg portions of the supporting means, of different lengths and secured at spaced points of the backing member. It may also have spaced portions slidably engaging the rod to provide for holding the backing member substantially at a normal to the partition means and to prevent sliding of the member when it is moved to an oblique position relative to the rod and partition means.

Other features, objects, advantages and capabilities are comprehended by the invention as will later appear and are inherently possessed by the invention.

Referring to the drawings illustrating an embodiment of the invention, Figure 1 is a top plan view of a filing device constructed in accordance with the invention; Figure 2 is a vertical sectional view taken in a plane represented by line 2-2 of Figure 1 of the

drawings; Figure 3 is a fragmentary transverse sectional view taken in planes represented by line 3-3 of Figure 2 of the drawings; and, Figure 4 is a fragmentary top plan view of a part of the backing means.

Referring now more in detail to the drawings, the embodiment selected to illustrate the invention is shown as comprising a drawer 1 having side walls 2, 3, 4 and 5 of which any two opposite side walls may be provided, such as side walls 3 and 5, with grooves 6, 7, 8 and 9, of which grooves 6 and 7 form one set of grooves, and grooves 8 and 9 form another set. It is to be understood that any number of sets of grooves may be provided as desired depending upon the size of the articles or cards to be filed in the filing space. In each set of grooves may be selectively inserted or extended the backing and filing mechanism added to the drawer. Such mechanism comprises a lower partition member 10 having its end extending into a set of opposed grooves such as grooves 6 and 7 or grooves 8 and 9, the member now being shown in grooves 8 and 9 in Figure 1 of the drawings. The upper edge 11 of the member 10 is preferably cut away to provide a space, the purpose of which is explained later. Upon the end portions 12 and 13 of the member 10 is supported a rod 14 having its ends extending into the grooves of a set, such as grooves 8 and 9. Above and upon the rod 14 is supported a second partition member 15 having its ends extending into the same grooves and also provided with a lower edge portion 16 cut away from the member to form a space above the rod.

Within the space provided between the partition means and the wall 2 of the drawer is laterally located a backing member 17 of any suitable construction or form and adapted to act as the backing support or member of a pile of cards or the like located in a filing space. This backing member may be moved forward or backward as desired preferably by sliding the same along the rod 14. This sliding may be effected by a supporting means 18 having leg portions 19 and 20 of different lengths and secured at the ends thereof to spaced points on the backing member by suitable securing means such as screws 21 and 22 as clearly shown in Figure 3 of the drawings. The supporting member 18

has also spaced and apertured portions 23 and 24 connected by a connecting portion 25 such that the portions 23 and 24 may slide along the rod 14. The spaced portions 23 and 24 are so spaced that if the packing member 17 be moved obliquely to the rod and the partition means, the portions 23 and 24 will lock with the rod, but when the partition member is normal to the rod it may be easily moved along the rod without the portions 23 and 24 locking therewith. The cut away portions of the partition members 11 and 15 below and above the rod is for providing a space for the sliding of the portions 23, 24 and 25.

As is apparent from Figure 1 of the drawings the only change made in the drawer 1 is the provision of grooves 6, 7, 8 and 9. The additional members comprise the partition means having members 10 and 15 and a slide rod 14 extending in these grooves. From the rod is supported the backing member 17 and the supporting member 18. In the full line showing of these members, the same are set for cards of a greater size and when the members are located in grooves 6 and 7, as for example the full line illustration shows the device set for cards which are 4 by 6 inches, and the dotted line position of the same members shows the filing spacing for cards that are of a size of 3 by 5 inches. The same backing member 17 may be used for smaller or larger sized cards, the space between the end of the member 17 and the walls 2 when the members are located for a larger card, not being sufficient to prevent an efficient backing of the cards.

While I have herein described and upon the drawings shown a particular embodiment of the invention, it is to be understood that the invention is not limited thereto but also comprehends other constructions, details and arrangements of parts without departing from the spirit thereof.

Having thus disclosed my invention, I claim:

1. A filing device comprising a drawer having opposite walls thereof provided with grooves, partition means in said grooves for providing a filing space between said means and a wall of the drawer, and a backing means carried by said means and located in said space.

2. A filing device comprising a drawer having opposite walls thereof provided with grooves, partition means in said grooves for providing a filing space between said means and a wall of the drawer, a backing member in said space, and means for slidably supporting said member on said partition means.

3. A filing device comprising a drawer having opposite walls thereof provided with grooves, partition means in said grooves for providing a filing space between said means and a wall of the drawer, a backing member

in said space, and a rod carried by said partition means and slidably supporting said member.

4. A filing device comprising a drawer having opposite walls thereof provided with grooves, partition means in said grooves for providing a filing space between said means and a wall of the drawer, a backing member in said space; a rod carried by said partition means, and means connected to said member and slidably connected to said rod.

5. A filing device comprising a drawer having opposite vertical walls thereof each provided with spaced grooves, means selectively extending in said grooves for providing different sized filing spaces between said means and another vertical wall of the drawer, and backing means carried by said first mentioned means and adapted for backing action in said different sized spaces.

6. A filing device comprising a drawer having opposite vertical walls thereof each provided with spaced grooves, partition means selectively extending in opposed grooves in said opposite walls, and a backing member carried by said means and extending laterally therefrom.

7. A filing device comprising a drawer having opposite vertical walls thereof each provided with spaced grooves, partition means selectively extending in opposed grooves in said opposite walls, a rod carried by said means, and a backing means slidably carried by said rod.

8. A filing device comprising a container having side walls provided with grooves, a lower partition member extending in said grooves, a rod extending in said grooves and supported on said lower partition member, an upper partition member extending in said grooves, and supported on said rod, and a backing member extending laterally from and being slidable on said rod.

9. A filing device comprising a container having side walls provided with grooves, a rod extending in said grooves, means in said grooves for holding the rod in place, and a backing member slidable on said rod and extending laterally from said rod.

10. In a filing device, backing means comprising a rod adapted to extend into grooves provided in side walls of a drawer, and a backing member slidable on said rod and extending laterally therefrom.

11. In a filing device, backing means comprising a rod adapted to extend into grooves provided in side walls of a drawer, a backing member extending laterally from said rod, means secured to said member and having spaced elements slidably connected to said rod.

12. In a filing device having backing means, a rod, a backing member extending laterally from said rod, a support having legs of different lengths secured to the back-

ing member at spaced points and being slidably mounted on the rod.

13. In a filing device having backing means, a rod, a backing member extending laterally from said rod, a support secured to the backing member and having spaced portion slidably engaging said rod.

14. A filing device comprising a drawer, a partition therein, a slide carried by the partition, and a backing member slidable along said slide and extending laterally from said partition for backing filing elements in the space in the drawer at the side of said partition.

15. A filing device comprising a drawer having opposite walls, partition means between said walls for providing a space between said means and a wall of the drawer, a rod supported by said means, and a backing member slidable on said rod and extending laterally from said means and into said space.

16. A filing device comprising a drawer having opposite walls, partition means between said walls for providing a space between said means and a wall of the drawer for accom-

modation in said space of filing elements of different widths, a backing member extending laterally into said space from said means and adapted to be located for backing filing elements of different widths, and means carried by said partition means for slidably supporting said backing member.

17. In a filing device, backing means comprising a rod supported between side walls and within the space of a drawer, and a backing member extending laterally from and slidable along said rod for backing action in the drawer space at one side of the rod.

18. In a filing device, backing means comprising a rod supported between side walls and within the space of a drawer, and a backing member extending laterally from and slidable along said rod for backing action in the drawer space at one side of the rod, said backing member having spaced elements slidably connected to the rod for locking therewith when the backing member is moved into angular relation with said rod.

In witness whereof, I hereunto subscribe my name to this specification.

MAYNARD HOLDING RAGGIO.

Certificate of Correction.

It is hereby certified that in Letters Patent No. 1,592,902, granted July 20, 1926, upon the application of Maynard Holding Raggio, of Chicago, Illinois, for an improvement in "Filing Devices," errors appear in the printed specification requiring correction as follows: Page 3, lines 6 and 7, claim 13, for the word "portion" read *portions*, and line 25, claim 16, before the word "said," first occurrence, insert the syllable *tween*; and that the said Letters Patent should be read with these corrections therein that the same may conform to the record of the case in the Patent Office.

Signed and sealed this 19th day of October, A. D. 1926.

[SEAL.]

WM. A. KINNAN,
Acting Commissioner of Patents.
